WILLIAM ROSS, OF SOUTH PORCUPINE, ONTARIO, CANADA.

CENTRIFUGAL PUMP.

1,293,938.

Specification of Letters Patent. Patented Feb. 11, 1919.

Application filed March 12, 1917. Serial No. 154,322.

To all whom it may concern:

Be it known that I, WILLIAM Ross, of South Porcupine, in the Province of Ontario, Canada, have invented certain new and useful Improvements in Centrifugal Pumps, of which the following is a specification.

This invention relates particularly to centrifugal pumps intended for moving liquids containing solid matter in suspension, and my object is to devise a pump for this purpose of increased durability and freedom from wear and to make all parts specially liable to wear readily accessible and removable for repairs or replacement.

I attain my objects by means of the constructions hereinafter described and illustrated in the accompanying drawings in which—

20 Figure 1 is a vertical section of a pump constructed in accordance with my invention;

Fig. 2 a plan view of the same;

Fig. 3 an end elevation of the same;

25 Fig. 4 an enlarged sectional detail illustrating the packing for the joint between the impeller and pressure casing;

Fig. 5 an elevation, partly in section of a double pump;

30 Fig. 6 a plan view of the same;

Fig. 7 a similar view showing a modification of the connections;

Fig. 8 a longitudinal section of a modification of the arrangement of the double 35 pump; and

Fig. 9 a vertical longitudinal section of a modification of the construction shown in Fig. 1.

In the drawings like numerals of reference indicate corresponding parts in the different figures.

Referring particularly to Figs. 1, 2 and 3, 1 is a base provided with suitable standards 2 carrying bearings for the shaft 3—4. 45 On one part of the shaft is secured a driving pulley 5. 6 is a combined main pump casing and suction chamber, preferably of cylindrical form as shown and provided with the end covers 7.

50 Each end cover is provided with a stuffing box 8 constructed substantially as hereinafter described. The ends of the parts of the shaft 3—4 are secured together by a

coupling sleeve 9, the ends of the parts of the shaft being threaded to screw into the 55 sleeve.

On this sleeve 9 is mounted the impeller 10 of any suitable type and provided at one or both sides with an inlet eye 11.

For use with fluids having gritty matter 60 in suspension, it is necessary to make the impeller of very hard material, which, therefore, is not readily machined. The hub of the impeller is therefore provided with a soft metal core 12, which can readily be 65 bored, keyseated and fitted on the sleeve 9. The stuffing boxes 8 are similarly constructed.

Each part of the shaft 3—4 is provided with a renewable protecting sleeve 13. 70 Within the stuffing box is fitted a removable neck ring 14. The gland packing 15 is placed within the stuffing box over the neck ring 14, and is engaged by the gland 16.

17 is a gland flange having contact by 75 means of a ball and socket joint with the end of the gland. Bolts 18 connecting the flange and the gland provide means for tightening the packings. Owing to the use of the ball and socket joint, unequal tightening of the bolts will not push the gland out of alignment. A grease cup 19 is provided for lubricating the neck rings 14.

Around the impeller is fitted the pressure casing 20. This casing is of the volute 85 form shown and is releasably held in position within the main casing preferably by means of a plurality of screws 21 threaded through the periphery of the main casing and engaging the periphery of the pressure 90 casing.

The main casing is provided with the inlet 22 and the outlet 23, which communicates with the outlet of the pressure casing as shown in Fig. 3.

To protect the exterior of the impeller from contact with the water in the main casing, I provide the pressure casing with cheek members 24, which are preferably formed separate from the casing and are applied thereto as shown, being provided with lips 25 engaging the outer side of the pressure casing, thus defining the position of the cheeks relative thereto.

These cheeks are removably held in place 105 preferably by means of screws 26 threaded

- through the cover plates 7 of the main casing. There must, of course, be a free running peripheral joint between the impeller and the stationary member in close proximity to which it rotates. In the present case, the joint being between the impeller and the pressure casing, or more properly the cheek member forming part of the casing, to keep this joint tight without undue wear I therefore provide the following packing means. An annular recess is formed in one of the relatively movable parts, preferably the impeller as shown in Fig. 4, and in this recess is loosely fitted a packing ring 27. Pressure from within the impeller will act against the side of this ring to crowd it against the far side of the annular recess, and thus maintain a tight lateral joint. Further, the pressure can get beneath the ring and press it outwardly against the face of the cheek or pressure casing with which it contacts. An absolutely tight joint is thus readily insured. The packing ring may be either simple or of a piece wound in spiral form.
- Considerable difficulty is experienced in centrifugal pumps in excluding grit from the shaft, neck rings, gland packings and glands hereinbefore referred to, and I have devised novel means for minimizing the accessibility of grit to these parts.
- Referring particularly to Fig. 4, it will be seen that the impeller at the inner side of the eye at each side is provided with an axially and radially directed extension 28, which terminates in a disk 29, which preferably extends into an annular chamber 30 in the side of the main casing, and preferably formed in the face of the stuffing box which forms part of the end cover of the casing. Into this annular chamber water is introduced through a pipe 31, which water may be under pressure so as to cause an outward flow around the edges of the disk 29. The disk 29 will preferably be provided with vanes 32, which, when the impeller is in rotation, will tend to draw water through the pipe 31 and expel it around the edge of the disk 29 under pressure. When such vanes are employed it will be seen that it is not essential that the water through the pipe 31 be supplied under pressure. With this arrangement it is practically impossible for grit to obtain access to the bearing surfaces of the pump.
- The mode of operation of the pump will be readily understood from the above description, but the method of obtaining access to and of removing the working parts requires some further explanation.
- The outer end of the shaft 4 is provided with a hole 33 into which a bar can be inserted and the shaft 4 rotated while the shaft 3 is held from rotation by the engagement of its pulley 5 with a driving belt. The shaft 4 may thus be unscrewed from its engagement with the coupling sleeve 9. The shaft may then be pushed endwise until it is clear of the stuffing box and gland. The cover 7 is then easily removed together with the stuffing box and gland. The outer cheek 24 may then be lifted out and the impeller and coupling sleeves screwed off the shaft 3. The pressure casing may easily be removed by releasing one of the screws 21 and with it will come the inner cheek piece 24. By reversing the operation the parts are easily reassembled.
- It will be understood, of course, that any of the parts in contact with the fluid and its suspended grit may be supplied with detachable liners such as commonly employed.
- In Fig. 5 I show a double pump constructed in accordance with my invention, the main pump casing being divided by a partition, and an impeller and pressure casing provided at each side of the partition. If the pumps are to be used in series, the outlet 23 of the pump at one side of the casing is connected with the inlet 22 of the pump at the other side of the casing by means of a pipe 35. In Fig. 7 I show an arrangement of the connections by means of which the pumps may be used either in parallel or in series. A suction pipe 36 is branched to connect with the inlets 22 to the main pump casing, and a discharge pipe 37 is branched to connect with the outlets 23. The pipe 35 is employed connected as shown in Fig. 6.
- In the pipe 35 is located a valve 38, and valves 39 and 40 are provided controlling respectively the branches of the discharge pipe 37 to the left hand outlet 23 and the branch of the suction pipe 36 leading to the right hand inlet 22. When the valve 38 is open and the valves 39 and 40 closed, the pumps operate in series. When the valve 38 is closed and the valves 39 and 40 open the pumps operate in parallel.
- In Fig. 8 I show a modification of the double pump in which the impeller has an eye at each side and is provided with a double discharge leading to a double pressure casing 42, and in which the partition 43 dividing the main pump casing is formed as part of the pressure casing. Such a pump may be operated if desired according to the arrangements shown in Figs. 6 and 7.
- In Fig. 9 I show an arrangement in which the impeller is provided with an eye at one side only. I show also in this figure a removable feed pipe 41, which leads from the inlet of the main casing to the eye of the impeller, and is held in position by means of a screw 45 screwed through the end cover of the casing. Such a feed pipe may, of course, easily be employed also with an impeller having an eye at each side. This feed pipe is particularly useful in moving fluids containing large stones, gravel and

the like, and may be omitted when fluids containing comparatively small particles in suspension are being moved.

What I claim as my invention is:

- 5 1. In a centrifugal pump, the combination of an impeller with an inlet eye at each side and a peripheral discharge; an undivided pressure casing surrounding the periphery of the impeller and provided with a suitable discharge; a pump casing forming a suction chamber surrounding the impeller and pressure casing and provided with an inlet opening in the plane of the impeller and a discharge opening communicating with the discharge of the pressure casing; an impeller shaft extending through each end of the casing; means for removably supporting the pressure casing within the pump casing; a removable, suitably held, stationary cheek piece at each side engaging the pressure casing and protecting the impeller. 70
- 10 2. In a centrifugal pump, the combination of an impeller with an inlet eye at each side and a peripheral discharge; a pressure casing surrounding the periphery of the impeller and provided with a suitable discharge; a pump casing forming a suction chamber surrounding the impeller and pressure casing and provided with an inlet opening in the plane of the impeller and a discharge opening communicating with the discharge of the pressure casing; an impeller shaft extending through each end of the casing; means for removably supporting the pressure casing within the pump casing; a removable, suitably held, stationary cheek piece at each side extending from the pressure casing and overlapping the impeller; and a removable end cover for the pump casing, the pressure casing and impeller being removable through the end of the casing when the said cover is removed. 80
- 15 3. In a centrifugal pump, the combination of an impeller with an inlet eye at each side and a peripheral discharge; a pressure casing surrounding the periphery of the impeller and provided with a suitable discharge; a pump casing forming a suction chamber surrounding the impeller and pressure casing and provided with an inlet opening and with a discharge opening communicating with the discharge of the pressure casing; an impeller shaft extending into the casing; means for removably supporting the pressure casing within the pump casing; a removable, suitably held, stationary cheek piece at each side engaging the pressure casing and protecting the impeller; and a removable end cover for the pump casing, the pressure casing and impeller being removable through the end of the casing when the said cover is removed. 90
- 20 4. In a centrifugal pump, the combination of an impeller with an inlet eye at each side and a peripheral discharge; a pressure casing surrounding the periphery of the impeller and provided with a suitable discharge; a pump casing forming a suction chamber surrounding the impeller and pressure casing and provided with an inlet opening in the plane of the impeller and a discharge opening communicating with the discharge of the pressure casing; an impeller shaft extending through each end of the casing; means for removably supporting the pressure casing within the pump casing; a removable, suitably held, stationary cheek piece at each side engaging the pressure casing and protecting the impeller. 95
- 25 5. In a centrifugal pump, the combination of an impeller with an inlet eye at each side and a peripheral discharge; a pressure casing surrounding the periphery of the impeller and provided with a suitable discharge; a pump casing forming a suction chamber surrounding the impeller and pressure casing and provided with an inlet opening in the plane of the impeller and a discharge opening communicating with the discharge of the pressure casing; an impeller shaft extending through each end of the casing; means for removably supporting the pressure casing within the pump casing; a removable, suitably held, stationary cheek piece at each side engaging the pressure casing and protecting the impeller; and means for removably supporting the pressure casing within the pump casing. 100
- 30 6. In a centrifugal pump, the combination of a divided shaft; a coupling sleeve releasably connecting the parts of the shaft; an impeller mounted on said sleeve and provided with an inlet eye and peripheral discharge; a pressure casing surrounding the periphery of the impeller and provided with a suitable discharge; and a pump casing surrounding the impeller and pressure casing and provided with an inlet opening and discharge opening communicating with the discharge of the pressure casing; a removable end cover for the pump casing through which the pressure casing and impeller are accessible and removable; and releasable means for supporting the pressure casing from the pump casing. 105
- 35 7. In a centrifugal pump, the combination of an impeller with an inlet eye and peripheral discharge; a pressure casing surrounding the periphery of the impeller and provided with a suitable discharge; cheek pieces at each side engaging the pressure casing and protecting the impeller; a pump casing surrounding the impeller and pressure casing and provided with an inlet opening and a discharge opening communicating with the 110
- 40 discharge of the pressure casing; a removable end cover for the pump casing, the pressure casing and impeller being removable through the end of the casing when the said cover is removed; and a removable end cover for the pump casing through which the pressure casing and impeller are accessible and removable; and releasable means for supporting the pressure casing from the pump casing. 115
- 45 8. In a centrifugal pump, the combination of an impeller with an inlet eye and peripheral discharge; a pressure casing surrounding the periphery of the impeller and provided with a suitable discharge; cheek pieces at each side engaging the pressure casing and protecting the impeller; a pump casing surrounding the impeller and pressure casing and provided with an inlet opening and a discharge opening communicating with the 120
- 50 discharge of the pressure casing; a removable end cover for the pump casing, the pressure casing and impeller being removable through the end of the casing when the said cover is removed; and a removable end cover for the pump casing through which the pressure casing and impeller are accessible and removable; and releasable means for supporting the pressure casing from the pump casing. 125
- 55 9. In a centrifugal pump, the combination of an impeller with an inlet eye and peripheral discharge; a pressure casing surrounding the periphery of the impeller and provided with a suitable discharge; cheek pieces at each side engaging the pressure casing and protecting the impeller; a pump casing surrounding the impeller and pressure casing and provided with an inlet opening and a discharge opening communicating with the 130
- 60 discharge of the pressure casing; a removable end cover for the pump casing, the pressure casing and impeller being removable through the end of the casing when the said cover is removed; and a removable end cover for the pump casing through which the pressure casing and impeller are accessible and removable; and releasable means for supporting the pressure casing from the pump casing. 135
- 65

- discharge of the pressure casing; a plurality of screws threaded through the ends of the casing and engaging the cheek pieces to hold them in place; and a plurality of screws 5 threaded through the periphery of the pump casing and engaging the pressure casing to hold it in place.
8. In a centrifugal pump, the combination of a plurality of impellers each with an inlet 10 eye and peripheral discharge; a pressure chamber for each impeller surrounding the periphery thereof and each provided with a suitable discharge; a pump casing surrounding the impellers and pressure casings; 15 a partition or partitions dividing the pump casing to form a separate chamber for each impeller and its pressure casing; an inlet and exit for each chamber, the latter communicating with the pressure casing; and a 20 pipe connecting the exit of one chamber with the inlet of the other.
9. In a centrifugal pump, the combination of a plurality of impellers each with an inlet eye and peripheral discharge; a pressure 25 chamber for each impeller surrounding the periphery thereof and each provided with a suitable discharge; a pump casing surrounding the impellers and pressure casings; 30 a partition or partitions dividing the pump casing to form a separate chamber for each impeller and its pressure casing; an inlet and exit for each chamber, the latter communicating with the pressure casing; and connections and controlling means 35 whereby the impellers may be used in series or in parallel.
10. In a centrifugal pump, the combination of a pump casing having a removable
- end; a divided shaft extending through the ends of the casing; a coupling sleeve releasably connecting the parts of the shaft; and an impeller mounted on said sleeve. 40
11. In a centrifugal pump, the combination of a pump casing; an impeller mounted therein having an inlet eye; an axial and radial extension of the impeller at the inner side of the eye extending to form an annular disk in close proximity to the side of the casing; and means for introducing water between the casing and said disk. 45
12. In a centrifugal pump, the combination of a pump casing; an impeller mounted therein having an inlet eye; an axial and radial extension of the impeller at the inner side of the eye extending to form an annular 50 disk in close proximity to the side of the casing; means for introducing water between the casing and said disk; and vanes on the outer face of said disk. 55
13. In a centrifugal pump, the combination of a pump casing; an impeller mounted therein having an inlet eye; an axial and radial extension of the impeller at the inner side of the eye extending to form an annular 60 disk in close proximity to the side of the casing; means for introducing water between the casing and said disk; and vanes on the outer face of said disk, an annular chamber being formed in the casing into which the 65 vanes extend and into which the water is led. 70

Signed at South Porcupine this 27th day of Feby. 1917.
